UNITED STATES PATENT OFFICE.

SAMUEL N. CRAGIN, OF AKRON, OHIO.

GARMENT-HANGER.

No. 818,748.

Specification of Letters Patent.

Patented April 24, 1906.

Application filed October 7, 1905. Serial No. 281,773.

To all whom it may concern:

Be it known that I, SAMUEL N. CRAGIN, a citizen of the United States, residing at Akron, in the county of Summit and State of Ohio, have invented new and useful Improvements in Garment-Hangers, of which the following is a specification.

This invention is a garment-hanger particularly adapted for hanging skirts and coats. The object of the invention is to form an improved device of the kind characterized by simplicity and cheapness and by an adjustment which may be quickly made to accommodate the hanger to garments of various sizes and to quickly attach the garment to or detach the same from the hanger.

In the accompanying drawings, Figure 1 is a side view of the hanger. Fig. 2 is an end view.

Referring specifically to the drawings, the hanger will be seen to comprise two parallel rods on which a hook is produced and a pair of projecting pieces which are slideable in and out on the rods and on which the garment is engaged.

A piece of stout wire is bent to form a hook 6, at the lower end of which it is bent out at an angle to form one side of an upper rod 7, at the outer end of which it is bent down and back to form a lower rod 8, and finally bent back to form the other side or half of the upper rod 7, and at its end is fastened by being wound around the shank of the hook, as indicated at 9. The rods 7 and 8 are parallel.

At 10 are indicated a pair of curved arms or pieces depending from the rods. These arms are mounted upon the rods by means of holes at 11, through which the lower rod 8 passes, and notches at 12, in which the upper rod 7 lies. Necessarily the wire is inserted through the holes 11 before being bent to its final shape. The lower ends of the arms 10 flare outwardly, as indicated at 13, thereby serving to support the skirt or coat hung thereon. The weight of the garment tends to throw the arms inwardly, and consequently produces a binding action at the holes 11, which prevents any movement of the arms. The location of the rod 7 in the

notches 12 serves to prevent any turning or side movement of the arms and increases the rigidity and strength of the device.

In placing a garment, such as a skirt, on the hanger one arm is caught on the waistband and the other arm is shoved in until it will pass within the band at the other end. Then the arm is drawn out or back and the weight allowed to come thereon. To detach the skirt, it is simply necessary to release the weight on one of the arms and push the same in along the rods until the skirt will drop off.

The arms 10 may conveniently be made of cast-iron or of wire bent to a similar shape. Inasmuch as the outer ends of the rods 7 and 8 are connected together or closed it is impossible for the arms 10 to be pulled off or to slip off and become lost, which is a decided advantage.

What I claim as new, and desire to secure by Letters Patent, is—

1. A garment-hanger comprising parallel rods located one above the other and provided with a hook, and a pair of depending arms slideable in and out on the rods and shaped to support a garment, each arm having an opening near the top thereof and another below the same, through which openings the upper and lower rods respectively extend, the arms being offset outwardly at their lower ends so as to bind against one of the rods, at the openings, when a garment is hung thereon.

2. A garment-hanger comprising a piece of wire bent to form a hook and two parallel rods located one above the other and connected together at their outer ends, and a pair of depending garment-supporting arms engaging and slideable on both of the rods and having notches in their upper ends, through which the upper rod extends, and holes below said notches through which the lower rod extends.

In testimony whereof I have signed my name to this specification in the presence of two subscribing witnesses.
